UNITED STATES PATENT OFFICE

2,344,405

PHOTOGRAPHIC PRINTING MACHINE

Garrison P. Grover, Minneapolis, Minn.

Application November 17, 1941, Serial No. 419,455

8 Claims. (Cl. 95—75)

My invention relates to photographic printing machines and has for an object to provide a highly practical and serviceable machine for the purpose.

An object of the invention resides in providing a photographic machine having a planiform transparent member for supporting a negative and a platen movable toward said support to bring a sensitized sheet of photographic printing paper in contact with the negative and in further providing a plurality of pressing members, each movable toward and from the support and engaging the platen at a different position to distribute the pressure uniformly upon the platen and produce intimate contact between the negative and the sheet of sensitized printing paper throughout the extent thereof.

Another object of the invention resides in providing a single operating member for operating the various movable parts of the invention, whereby precise timing and unity of operation of all parts of the invention is procured.

A still further object of the invention resides in providing a constantly driven feed roll for moving the printing paper through the machine and in providing a pressure roll periodically movable toward and from the said feed roll to procure movement of the paper.

Another object of the invention resides in providing a number of electric lights for printing the sensitized paper and in providing a timing device for shutting off said lights after the sensitized sheet has been printed.

An object of the invention resides in providing means for adjusting the period of time measured by said timing device.

A still further object of the invention resides in providing a machine with a case supporting the operating mechanism of the device and in employing a removable drawer within the case and supporting a transparent support for the negative and a screen for use in conjunction therewith.

Other objects of the invention reside in the novel combination and arrangement of parts and in the details of construction hereinafter illustrated and/or described.

In the drawings:

Fig. 1 is a plan view of a photographic printing machine illustrating an embodiment of my invention.

Fig. 2 is a front elevational view of the structure shown in Fig. 1.

Fig. 3 is an elevational sectional view taken on line 3—3 of Fig. 1.

Fig. 4 is an elevational sectional view taken on line 4—4 of Fig. 1.

Fig. 5 is a fragmentary elevational sectional view taken on line 5—5 of Fig. 1.

Fig. 6 is a wiring diagram of the invention.

My invention comprises a case 10 having a bottom 11, a rear wall 12, side walls 13 and 14 and a front wall 15. These walls may be connected together in any suitable manner and may be constructed of wood or any other suitable material. The front wall 15 falls short of the uppermost portion of the case to provide an opening 17 into the interior of the case and at the front thereof which opening is designated by the reference numeral 18. A door 19, connected to the front wall 15 by means of hinges 21 serves to close the opening 18. A knob 22 attached to said door permits of opening and closing the same and a suitable latching device (not shown) holds the door in closed position.

Secured to the interior of the case 10 are a number of rails 23 which extend perimetricaly about the walls of the case intermediate the upper and lower ends thereof and which divide the case into an upper compartment 24 and a lower compartment 25. In the lower compartment 25 are mounted a number of electric light sockets 26, having suitable electric lights 27 in the same. The rails 23 form a support for a rack 28, which is in the form of a drawer and may be inserted into the compartment 24 and removed therefrom through the opening 18 in case 10.

The rack 28 is U-shaped in form and consists of two runners 29 connected together at their rearward ends by means of a connecting piece 31. The runners and connecting piece are of substantially the same width as the width of the rails 23. Attached to the uppermost portions of the runners 29 and the connecting piece 31 is a frame 32 rabbeted as indicated at 33 to receive a plate of glass 34, which serves as a support for the negative. The height of the runners 29 and connecting piece 31 and of the frame 32 is such that the upper surface of the plate of glass 34 becomes disposed at the uppermost portion of the case 10 and flush with the upper edges of the walls 13 and 14 of case 10. This plate of glass is secured in the frame 32 in any suitable manner. The electric lights 27 are so disposed that the light rays from the same pass upwardly and through the plate 34. In the runners 29 and also in the connecting piece 31 are formed grooves 35 in which may be placed suitable screens which control the flow of light from the electric lights 27 through the plate 34. The rails 23 form a light

break between the case 10 and rack 28, preventing light from passing between the runners 29 and the walls 13 and 14 of the case, thus preventing exposing of the sensitized sheet outwardly of the negative.

The negatives from which the prints are to be made are placed directly upon the uppermost surface of the plate of glass 34 and secured thereto by means of suitable adhesive applied directly to the glass or negative or by means of adhesive 10 tape or in any other suitable manner. The sensitized paper used for printing is indicated by the reference numeral 36 in the drawings and passes over the negative carried by the glass plate 34. The bulk of sensitized paper is in roll 15 form, as indicated at 37 and the portion 36 is unrolled therefrom as the same is used. The construction for supporting and feeding the paper will now be described.

Attached to the upper edges of the side walls 13 and 14 by means of screws 38 are two supporting bars 41 and 42. These bars have projecting portions 43 extending outwardly beyond the side wall 14, which are formed with bearings 44 rotatably supporting a shaft 45. Mounted on this shaft is a roll 46 of suitable resilient material, such as rubber or the like, which is so situated that the lowermost element thereof is substantially at the plane of the upper surface of the glass plate 34 and at the plane of the sheet 20 of sensitized paper 36. Below the roll 46 are two smaller pressure rolls 47 and 48, which are rotatably mounted on spindles 51 secured to two arms 52 and 53 disposed on opposite sides of the machine and straddling the case 10. The arms 52 25 and 53 are pivoted on stub shafts 54 secured to the rear wall 12 of case 10 and to the forward edge of the side wall 14 of said case by means of screws 55. The arm 52 forms part of a lever 56 which has another arm 57 projecting outwardly therefrom. The arm 57 is adapted to be engaged by a cam 58 to be presently described in detail by means of which the two pressure rolls 47 and 48 are urged toward the feed roll 46. A compression coil spring 59 serves to withdraw the rolls 47 and 48 from engagement with the roll 46 and maintains the arm 57 in engagement with the cam 58. This spring is secured at one end to one of the spindles 51 and at its other end to a screw eye 61 secured to the side 30 wall 14 of case 10.

The roll 37 of sensitized paper is wound on a tubular core 62 which has a fairly large central hole 63 therein. The roll 37 is rotatably mounted on a spindle 64, which passes through the hole 63 in core 62 and which is received in openings 71 and 72 in brackets 66. The brackets 66 are attached to the side wall 13 of case 10 by means of screws 67, best shown in Figs. 1 and 4. The opening 71 opens upwardly so that the spindle 64, with the roll 37 mounted thereon, may be readily mounted in the openings in the said brackets. This spindle 64 is formed with shoulders 68 near its ends which engage the said brackets and restrain endwise movement of the spindle. The spindle 64 is so situated that the uppermost element of the roll 37 is substantially in the plane 35 of the uppermost surface of the plate of glass 34.

In the exposure of the sensitized paper, it becomes necessary to place the same in intimate contact with the negative. For this purpose, a platen 73 is employed which is provided with a flexible facing 74 of rubber, felt or some similar cushioning material. This platen has attached to it four guide rods 75 which extend up- 40

wardly through suitable openings 76 in two cross bars 77 and 78 secured to the supporting bars 41 and 42 by means of screws 79. Springs 81 encircle the said rods and are seated at their lower ends against the bars 77 and 78 and at their upper ends against washers 82 encircling said rods and held in position thereon by means of cotter pins 83. These springs serve to draw the platen 73 upwardly to relieve pressure upon the sheet of sensitized paper 36 and to permit the feeding thereof by means of the feed roll 46.

Extending across the platen 73 and adjacent the bars 75 are two shafts 84 and 85 which are journaled in bearings 86 formed on the supporting bars 41 and 42. Each of these shafts has two cams 87 on it, which cams are adapted to engage the upper surface of the platen 73. When the shafts 84 and 85 are rotated, the cams function to force the platen downwardly and to exert pressure upon the sensitized sheet 46 forcing the same into intimate contact with the negative mounted on the glass plate 34.

The two shafts 84 and 85 are driven in unison by means of a chain 88 which passes over two sprockets 89 and 91, secured to the said shafts 25 84 and 85, respectively. These two sprockets are the same size, so that the two shafts run in the same direction and at the same rate of speed. This causes all of the cams 87 to travel in unison with the platen to move vertically in parallelism with the upper surface of the glass plate 34.

For the purpose of driving the various parts of my improved photographic printing machine, I employ an electric motor 92, shown in Fig. 1. This motor has a base 94 which is bolted to a bed plate 95 secured to two cleats 96 which extend below the bottom 11 of case 10 and are secured thereto. The motor includes a transmission reduction unit 97 which is provided with a drive shaft 98 traveling at a greatly reduced rate of speed. Inasmuch as the construction of the motor 92 and the reduction of the transmission 97 are well known in the art and form no particular feature of the invention, the same have not been shown in detail in this application.

The shaft 98 has secured to it a bushing 99 which has attached to the end of it a sprocket 101. This sprocket drives a chain 102 which meshes with said sprocket and which also meshes with a sprocket 103 rotatably mounted on a stub shaft 104 attached to the rear wall 12 of case 10. The said chain additionally meshes with a sprocket 105 secured to shaft 45, a sprocket 106 secured to shaft 84 and another sprocket 107, rotatably mounted on another stub shaft 108 also secured to wall 12 of case 10. When the motor 92 is operated, all of these sprockets are rotated and the various parts connected therewith are driven.

The sprocket 103 has secured to it the cam 58 previously referred to, which, when the said sprocket is rotated, swings the lever 56 to move the rolls 47 and 48 toward the feed roll 46 to bring the paper in engagement therewith to procure travel of the paper.

The sprocket 107 has attached to it a disk 109 which is provided with a number of spaced holes 110 arranged in the arc of a circle. This disk has permanently attached to it on the front side thereof a pin 111 and on the rear side thereof a pin 112 which is insertable into any of the holes 110 in the said disk. These pins operate a switch 113, which consists of a tube of mercury 114 adapted to open and close a circuit through two contacts 115 and 116. The tube 114 is mounted

on a tube holder 117 which is pivoted on a pintle 118 secured to a standard 119 attached to the bed plate 88 by screws 120. The mounting 117 has a depending arm 121 which is formed with a notch 122 therein adapted to receive a pin 123 secured to the standard 119. By means of said notch, the extreme movements of the switch 113 are controlled, so that the circuit through the contacts 115 and 116 are either open or closed when the tube holder is in its extreme position. Acting between a hook 124 on the holder 117 and another hook 125 on the standard 119 is an over-center spring 126 which urges the switch tube to assume either of its extreme positions.

The holder 117 has attached to it an arm 127 which is provided with two fingers 128 and 129 issuing therefrom and best shown in Fig. 1. The finger 128 lies in the path of movement of the pin 111, while the finger 129 lies in the path of movement of the pin 112. It will thus be comprehended that the switch 113 is shifted from open to closed position and vice versa through the disk 109, as the same rotates and that the time during which said switch remains closed depends upon the particular hole 110 of disk 109 in which the pin 112 is inserted.

The circuit for operating my improved photographic printing machine is shown in Fig. 6 and includes a line 130 having conductors 131 and 132, which line is energized from any suitable source of electric current. The conductor 131 is directly connected to the contact 116 of switch 113. The various lights 27 are each connected in a branch circuit 133 which branch circuits are connected to the conductor 132 and to another conductor 134, which, in turn, is connected to the contact 115 of switch 113. The circuits 133 also include manually operated switches 135, by means of which one or more of the lights 27 may be connected to or disconnected from the circuit. The motor 92 is connected in a branch circuit 136 which is connected across the conductors 131 and 132 of line 130. This circuit also includes a manually operated switch 137, by means of which the said motor may be energized.

The manner of using my invention is as follows: When the machine is first started, the motor is first allowed to run a sufficient length of time until the cams 87 permit the platen 73 and facing 74 to ascend and clear the negative on the glass plate 34 and is then stopped. The roll 37 of sensitized paper is then slipped over the spindle and the same inserted into the openings 71 and 72 on brackets 66. The sheet 36 is then fed through the machine over the negative, which is mounted on the glass plate 34 and the said sheet finally threaded in between the feed roll 46 and the pressure rolls 47 and 48. The machine may now be run continuously. Upon feeding of the paper along the negative, the platen 73 remains in its ascended position. During this procedure, the switch 113 is shut off as shown in Fig. 3, and the electric lights 27 are out, so that movement of the paper without exposure is procured. When the arm 57 reaches the low spot of the cam 58, the rolls 47 and 48 are moved away from the roll 46 and feeding of the paper terminates. The platen 73 then descends and clamps the sheet 36 of sensitized paper against the negative. As soon as this occurs, the pin 111 on disk 109 engages the finger 128 of arm 127 and swings the switch 113 in a manner to close the circuit therethrough. Exposure of sensitized sheets now occurs and continues until the pin 112 strikes the

finger 129 and moves the switch 113 into opening position. When this occurs, cams 87 release the platen 73 and the feed roll 46 and pressure rolls 47 and 48 draw the exposed portion of the sheet out of the machine.

It will readily be comprehended that by use of suitable screens, which are mounted in the grooves 35 of the rack 28, suitable photographic effects may be procured. In the mounting of the 10 film on the plate 34, the rack is removed from the case 10. Upon use, the rack is inserted back into the case and the door 18 closed. If it becomes desirable to vary the amount of exposure, the same may be accomplished by shifting the pin 112 into 15 another of the openings 110 and also by controlling the number of lights used by means of the switches 135. Since my machine is motor-driven, it will be comprehended that the same will operate continuously and make successive exposures on 20 the sensitized sheet which passes over the negatives on the glass plate 34.

The advantages of my invention are manifest. The machine is extremely simple in construction and is highly practical and effective in use. By means of the four cams employed which engage the platen at different localities, movement of the platen in parallelism with the surface of the glass plate and film is procured. All of the operating parts of the invention being driven by a single driving member, unity of operation and positiveness in action results. Applicant, with his novel feed device, produces positive movement of the printing paper through the machine and causes accurate arrest of the paper, whereby waste of the paper is minimized. By means of the timing mechanism utilized by applicant, the printing of the paper can be accurately controlled. Applicant's rack for supporting the transparent negative support and the screens used, being removable from the case, permits of readily attaching the negative to the support and of conveniently changing the screens. By means of the rails on which the drawer of the invention is supported, a light break is provided between the two compartments between the case, so that leakage of light to expose undesired portions of sensitized paper is prevented.

Changes in the specific form of my invention, as herein described, may be made within the 50 scope of what is claimed without departing from the spirit of my invention.

Having described my invention, what I claim as new and desire to protect by Letters Patent is:

1. In a photographic printing machine, a 55 transparent support for a negative, a platen superimposing said support, means for guiding said platen for movement toward and from said support, a plurality of spaced shafts geared to each other and extending across said platen, each of said shafts having a plurality of cams thereon, all of said cams having corresponding cam surfaces adapted to produce uniform movement of the platen toward the support, a sprocket on one of said shafts, a feed roll, a 60 sprocket for driving said feed roll, and a single chain meshing with all of said sprockets for operating said cams and feed roll and means cooperating with said feed roll for rendering the same effective during disposition of the platen away from said support.

2. In a photographic printing machine, a 65 transparent support for a negative, a platen superimposing said support, means for guiding said platen for movement toward and from said support, a plurality of spaced shafts geared to each

other and extending across said platen, each of said shafts having a plurality of cams thereon, all of said cams having corresponding cam surfaces adapted to produce uniform movement of the platen toward the support, a sprocket on one of said shafts, a feed roll, a sprocket for driving said feed roll, a pressure roll, means for urging said pressure roll against said feed roll, said means including a sprocket, and a single chain meshing with all of said sprockets for causing movement of said pressure roll toward the feed roll when the platen is disposed away from the support and movement of the platen toward the support when the pressure roll is away from the feed roll.

3. In a photographic printing machine, a case having a transparent support for a negative, a feed roll carried by said case for moving a sensitized sheet toward the negative, means for continuously rotating said feed roll, a lever pivoted to said case and having two arms, a pressure roll journaled in one of said arms and adapted to be moved toward and from said feed roll and means engaging said other arm and periodically swinging said lever to bring said pressure roll into engagement with said feed roll.

4. In a photographic printing machine, a case having a transparent support for a negative, a platen superimposing said support, means carried by said case for guiding and periodically moving said platen toward and from said support, a feed roll carried by said case, means for continuously rotating said feed roll, a lever pivoted to said case and having two arms, a pressure roll journaled in one of said arms and adapted to be moved toward and from said feed roll, a cam adapted to engage the other arm of said lever and serving periodically to bring said pressure roll into engagement with said feed roll in synchronism with the movement of the platen.

5. In a photographic printing machine, a support for a negative, means for guiding a sheet of sensitized paper along said negative, a feed device for causing movement of said sensitized paper, an electric light for printing said sensitized sheet, a circuit including a switch for energizing said light, said switch having a movable part, a revolute member, a lever connected to said movable part and having two fingers thereon, two lugs on said revolute member, one of said lugs being adapted to engage one finger and move the movable part of the switch into closing position, the other of said lugs being adapted to engage the other finger and move the movable part of the switch into opening position.

6. In a photographic printing machine, a sup-

port for a negative, means for guiding a sheet of sensitized paper along said negative, a feed device for causing movement of said sensitized paper, an electric light for printing said sensitized sheet, a circuit including a switch for energizing said light, said switch having a movable part, a revolute member, a lever connected to said movable part and having two fingers thereon, a lug on said revolute member adapted to engage one of said fingers to move said part of the switch to closing position, a plurality of circumferentially arranged holes in said revolute member and a pin insertable into any of said holes for engaging the other finger to move the movable part of the switch into opening position.

7. In a photographic printing machine, a support for a negative, a platen movable toward and from said support, means including a sprocket for so moving said platen intermittently to engage the same with a sensitized sheet overlying a negative on said support, a feed roll having a sprocket, a pressure roll intermittently engageable with said feed roll, means including a sprocket for actuating the pressure roll, said rolls cooperating to advance said sensitized sheet along said support at the time of disengagement of the platen from the sheet, electric illuminating means for causing the printing of said sensitized sheet through said support and the negative thereon, a circuit for energizing said illuminating means, said circuit including a switch, adjustable switch actuating means including a sprocket, and a single drive chain meshing with all of said sprockets and through the same causing the actuation of their said respective means.

8. In a photographic printing machine, a case having an opening at the top thereof, means for feeding a strip of sensitized paper across the top of said case from end to end thereof over said opening, said feeding means including parts disposed at one side of the case, said case having a doorway in the other side thereof and a door for closing said doorway, a drawer horizontally 45 slideable sidewise into and out of said case through said doorway, a transparent support for a negative carried by said drawer and having its supporting surface in a plane subjacent to that of said strip of sensitized paper, and illuminating 50 means within the case beneath the drawer, said drawer, when outwardly drawn, offsetting said transparent support to one side of said strip of paper in an accessible position unobstructed thereby.

GARRISON P. GROVER.
